Primary Examiner — Samantha Q Lawrence(74) *Attorney, Agent, or Firm* — Wood Herron & Evans LLP(57) **CLAIM**

The ornamental design for a sanitary article, as shown and described.

DESCRIPTION

FIG. 1 is a top perspective view of a sanitary article showing our new design.

FIG. 2 is a top plan view thereof.

FIG. 3 is a bottom plan view thereof.

FIG. 4 is a left side elevational view thereof.

FIG. 5 is a right side elevational view thereof.

FIG. 6 is a front elevational view thereof; and,

FIG. 7 is a rear elevational view thereof.

The outer-most broken line perimeter shown in FIGS. 1-2 represent the bounds of the claim and form no part of the claimed design. The remaining broken lines shown in FIG. 1-2 and FIGS. 4-7 illustrate portions of the sanitary article and form no part of the claimed design.
